UNITED STATES PATENT OFFICE.

RONALD D. MAYER, OF TULSA, OKLAHOMA.

OIL-BURNER.

1,369,688.

Specification of Letters Patent. Patented Feb. 22, 1921.

Application filed July 14, 1919. Serial No. 310,552.

To all whom it may concern:

Be it known that RONALD D. MAYER, a citizen of the United States, residing at Tulsa, in the county of Tulsa and State of Oklahoma, has invented certain new and useful Improvements in Oil-Burners, of which the following is a specification.

This invention relates to new and useful improvements in an oil burner.

10 One object of the invention is to provide a burner of the character described which has been specially designed for use where crude oil is employed as a fuel.

15 Another object of the invention is to provide a burner of the character described whereby steam is combined and mingled with the fuel, by means of which a vapor is produced which is highly combustible and will produce intense heat.

20 A further feature of the invention resides in the provision of a movable heat absorbing shell which may be carried back and forth relative to the burner proper, thus increasing or decreasing the heating surface, 25 as may be desired.

A still further feature of the invention resides in the provision of means for drawing off and utilizing the surplus gas generated within the burner.

30 With the above and other objects in view, the invention has relation to certain novel features of construction, operation and arrangement of parts, an example of which is given in this specification and illustrated in 35 the accompanying drawings, wherein:

Figure 1, is a plan view of a furnace showing the burner applied thereto, and

Fig. 2, is an enlarged longitudinal sectional view of the burner.

40 Referring now more particularly to the drawings, wherein like numerals of reference designate similar parts in each of the figures, the numeral 1, refers to the furnace as a whole, having parallel brick walls 2 45 and 3, spaced apart therein and forming the combustion chamber 4, between them. Said brick wall 3 is provided with an opening 5 through which the burner may be inserted into the combustion chamber as shown

50 in Fig. 1. The numeral 6, designates a steam line which is controlled by the valve 7 and which terminates in a tubular steam chamber 8, whose free end is formed with a discharge nozzle 9. Arranged concentrically within the steam chamber, there is the tubing 10, which is fixed therein, and which

is spaced from the inner wall of said chamber. This tubing carries a spiraled fin 11, which spans the space between said tubing and the steam chamber wall, and which 60 gives a rotating or spiraled movement to the steam that passes under pressure from the steam line 6, through said chamber and is discharged out at the nozzle 9. The numeral 12 refers to an oil line, which is 65 controlled by the valve 13, and which enters and terminates in the steam chamber, and through which the oil is discharged into said chamber. This oil is caught up by the current of steam and carried up through 70 the steam chamber in a spiraled movement and is sprayed out by said steam through the nozzle 9 into said chamber in a vaporized form. Leading from the tubing 10, there is a gas pipe 14 which is controlled 75 by the valve 15 and the surplus gas collecting in the steam chamber enters the port 16, and the gas pipe 14 and is carried away to be utilized for any purpose desired. Surrounding the steam chamber 8, there is a 80 shell 17, having radiating vanes or fins and composed preferably of the mixture of copper and tantalum. This shell is slidably mounted on the steam chamber 8, and is movable through the instrumentality of 85 a manual rod 18, which is fastened thereto. The shell 17 is located within the combustion chamber and absorbs heat, to a high degree, but is not easily melted and will consequently make the steam chamber very hot 90 so as to vaporize the fuel therein. When the shell is moved inwardly toward the nozzle 9, it will be entirely within the combustion chamber and will become heated to a high degree, but it may be withdrawn 95 partly out of the combustion chamber, thereby reducing the heat thereof. The burner, may, therefore be regulated in a large degree by adjusting said shell on the steam chamber.

100 What I claim is:

1. An oil burner including a steam chamber, one end of which terminates in a nozzle, a steam line entering the other end of said chamber, spiraled baffles within the chamber, a fuel line discharging fuel within said chamber, a gas delivery line leading from said chamber, a shell surrounding said chamber having radiating vanes therearound and a manual means for adjusting 105 said shell back and forth on said chamber.

2. An oil burner including a tubular

steam chamber, one end of which terminates in a discharge nozzle, a spiraled baffle within said chamber, a steam line and a fuel oil line entering said chamber, a gas delivery line leading from said chamber and a heat absorbing shell mounted on said chamber, said shell having vanes radiating therefrom.

In testimony whereof I have signed my name to this specification in the presence of two subscribing witnesses.

RONALD D. MAYER.
